Durham O. Abel,

By Hindlee Parsons
his ATTORNEY

UNITED STATES PATENT OFFICE.

DURHAM O. ABEL, OF YOUNGSTOWN, OHIO.

MOWING-MACHINE.

SPECIFICATION forming part of Letters Patent No. 425,968, dated April 22, 1890.

Application filed November 24, 1886. Serial No. 219,837. (No model.)

To all whom it may concern:

Be it known that I, DURHAM O. ABEL, a citizen of the United States, residing at Youngstown, in the county of Mahoning and State of 5 Ohio, have invented certain new and useful Improvements in Mowing-Machines; and I do hereby declare the following to be a full, clear, and exact description of my invention, such as will enable others skilled in the art to which 10 it appertains to make and use the same, reference being had to the accompanying drawings, which form part of this specification.

My invention relates to the mechanism by 15 which the points of the guard-fingers are raised or depressed, or what is commonly known in the art as "tilted." It is desirable that the shoe which carries the finger-bar and the cutting apparatus should tilt or rock as nearly on a line as possible with the center of 20 the sickle-eye, so that the register of the knives or sickle with the guard-fingers may not be changed by the different positions which the shoe may assume in tilting. This has been accomplished hitherto by hanging 25 the tilting shoe on an overhanging arc of the main shoe, around which it rolls, and the center of whose motion is that of the sickle-eye. (Vide patent granted F. H. Bartlett, No. 340,083, April 20, 1886.) The objection to this 30 construction is that the mechanism is somewhat cumbersome and expensive to manufacture, and the center of movement of the tilting shoe being in advance of the center longitudinal line of the finger-bar the latter is 35 not readily or easily rocked. In order to remedy these defects, I have pivoted the tilting shoe on the center longitudinal line of the finger-bar, or nearly so, to the main shoe by a pin or bolt passing through lugs suitably 40 perforated in the tilting and main shoes. The sickle-eye is necessarily by this construction somewhat in advance of the pivot on which the shoe tilts; but the pivot of the tilting shoe is so near the plane of reciprocation of the 45 sickle-eye that the register of the knife or sickle is not materially changed. The tilting shoe being by this arrangement pivoted at or near the center of gravity of the finger-bar and cutting apparatus, the tilting of the shoe is 50 more easily effected, and I have found in practice that by disconnecting the tilting bar from the tilting shoe the cutting apparatus will pass

readily over obstructions and conform to the inequalities of the ground. I also provide the tilting shoe with ears or lugs, which, taking 55 into suitable grooves in the main shoe, prevent lateral displacement of the finger-bar and assist in maintaining the cutting apparatus at right angles to the line of draft.

Referring to the accompanying drawings, 60 forming part of this specification, and in which similar letters of reference indicate like parts, Figure 1 is a front perspective view of a mowing-machine embodying my invention. Fig. 2 is a perspective view of the main shoe and 65 the tilting shoe, showing their pivotal connections; Fig. 3, a perspective view of the main shoe; Fig. 4, a perspective view of the tilting shoe. Fig. 5 is a perspective view showing the relation of the sickle-eye or pitman-con- 70 nection and the pivot of the tilting shoe.

A A are the carrying and driving wheels mounted upon the axle A', from which motion is communicated in any well-known way to the crank-wheel A² and pitman A³. The tilting shoe B has the groove b, in which the finger-bar b' is bolted by the bolts b² b³, which also secure the sickle-holder b³ (see Fig. 1) in place. The main shoe B' is formed on the forward end of the tubular arm B², through which 80 the rod or shaft b⁴ passes, the extreme ends of the rod b⁴ being secured in a down-hanger b⁵ from the axle and in the coupling-arm B³ of the frame. The rod b⁴ forms a pivot on which the tubular arm B², carrying with it the tilting shoe and the cutting apparatus, may be 85 rocked, so as to fold the finger-bar or move it from a horizontal into a vertical position. The sides of the tilting shoe B are formed with the lugs c c', which take, respectively, into the 90 grooves c² c³, formed on the sides of the main shoe B', and also with the lug c⁴, which is perforated at c⁵ c⁶ at the longitudinal center of the finger-bar. The main shoe is formed with the lug d, perforated at d', and a pivot bolt or 95 pin d², (see Fig. 2,) passing through the holes d' c⁶, pivotally secures the tilting shoe B to the main shoe B'. The rod E is connected with the tilting shoe B at c⁵, and also with a suitable tilting and adjusting lever F, within 100 reach of the driver and of any well-known form of construction.

The sickle or scythe eye is reciprocated by the pitman just in front of the lug d, and its

distance from the said lug in advance thereof is not sufficient to materially change the register of the knife when the shoe is tilted.

Having now described my invention, what I claim as new, and desire to secure by Letters Patent, is—

1. The combination, in a mowing-machine, of the main shoe, a vertical perforated lug thereon, the tilting shoe, the finger-bar secured thereto, a vertical perforated lug on the tilting shoe, and a pivot bolt or pin passing through the perforated lugs on the center longitudinal line of the finger-bar, substantially as and for the purpose specified.
- 15 2. The combination, in a mowing-machine, of the main shoe, a vertical perforated lug thereon, the tilting shoe, the finger-bar secured thereto, a vertical perforated lug on the tilting shoe, a pivot-pin passing through the

vertical perforated lugs at the center longitudinal line of the finger-bar, grooves at the side of the main shoe, and ears at the side of the tilting shoe taking into the grooves in the main shoe, as and for the purpose specified.

3. The combination of the main shoe, the tilting shoe, and the finger-bar carried by the tilting shoe, the latter being pivoted to the main shoe on the center longitudinal line of the finger-bar, and an adjusting-lever connected to the tilting shoe, substantially as and for the purpose specified.

In testimony whereof I hereunto affix my signature in the presence of two witnesses.

DURHAM O. ABEL.
